His Attorney.

UNITED STATES PATENT OFFICE.

VINCENT S. GAINES, OF WEBSTER GROVES, MISSOURI.

MECHANICAL TOY.

1,315,108.

Specification of Letters Patent.

Patented Sept. 2, 1919.

Application filed February 16, 1918. Serial No. 217,545.

To all whom it may concern:

Be it known that I, VINCENT S. GAINES, a citizen of the United States, residing at Webster Groves, St. Louis county, and State of Missouri, have invented a new and useful 5 Mechanical Toy, of which the following is a specification.

This invention relates to a new and useful 10 mechanical toy, and comprises the novel construction and arrangement of parts herein- after disclosed.

An object of the invention is the production 15 of an inexpensive automatically operable mechanical toy which will be durable in construction and which may be readily operated by unskilled persons.

Another object of the invention is to provide 20 a mechanical toy made of few and simple parts and which may be folded so that it may be readily packed for distribution and adjusted for operation.

Another object of the invention is to provide 25 a mechanical toy including a load-receiving hopper, a movable member carrying load-receiving receptacles with automatic means for discharging the load from the hopper into the receptacles, whereby the toy is operated automatically.

With the foregoing and additional features 30 and advantages in view, I have produced the invention hereinafter disclosed, reference being made to the accompanying drawing, in which—

Figure 1 is a plan view of the toy embodying the invention.

Fig. 2 is a sectional view of the toy taken substantially on the line 2—2 of Fig. 3.

Fig. 3 is an elevation of the toy set up for operation.

As illustrated in the drawing the base or support for the toy includes a frame member 40 bent to form a horizontal leg 1 which is down-turned at its extremities forming feet 2. A support in the form of a horizontal leg 3 which is down-turned at its extremities to form feet 4 is centrally pivoted to the leg 1 and secured in movable relation therewith by a rivet 5 so that it may be turned in parallel alinement with the member 1—2 when 45 the toy is collapsed for packing purposes and adjusted at right angles thereto, as illustrated in the drawing, when the toy is to be supported upon a horizontal surface.

Side standards 6 extend upwardly from 50 the extremities of the feet 2, being preferably formed from the same strip of metal.

The side standards 6 incline inwardly at their upper ends, being curved inwardly at 55 7, from the inner extremities of which they are upturned forming parallel sections 8.

The load-receiving hopper which is supported at the upper part of the frame comprises a circular dish-shaped load receiving section 9 having an up-turned marginal flange 10 formed therewith. In the bottom wall of the section 9 is a spiral groove 11 which inclines downwardly from its outer end to the center of the member 9, whereat a rectangular opening 12 is formed. A rectangular chute 13 communicates with the opening 12, being attached to the end face of the member 9 surrounding the opening 12. In each of opposite walls of the chute 13 a pair of straps 14 are formed which fit over 70 the extensions 8 of the standards thereby removably supporting the hopper thereon. The lower extremity of the two walls of the chute, at right angles to the walls in which the straps are formed, are bent outwardly 75 forming downwardly curved extensions 15 which serve as guides in connection with discharging the load from the hopper. At the bottom edge of each of the side walls of the chute, which are disposed at right angles 80 to the walls having the extensions 15, are in-turned lips or flanges 16 which incline downwardly to the center, there being an open space 17 between the edges of the flanges on each of the walls.

A lever 18 connected with a lever support 19 is mounted in the standards 6 by pivoting the reduced ends 20 of the support 19 in openings 21 through each of the standards 6 in horizontal alinement, so that it 90 will be freely movable beneath the hopper. At one end the lever 18 is up-turned as indicated at 22, a counterweight 23 being held between the up-turned end 22 and the adjacent face of the lever. Near the opposite end of the lever and attached thereto is a pair of load-receiving receptacles 24, said receptacles being mounted on either side of the axis of the lever. The receptacles 24 are open at the top and have in-turned 95 flanges 25 at their outer ends.

The lever 18 has an extension of reduced width above the upper edge of the receptacles which forms a finger 26 which extends through the space 17 into the lower portion 100 of the chute of the hopper. The counterweight 23 and the arms of the lever 18 are so 105

adjusted that normally, the end of the lever carrying the receptacles will be held in vertical position below the center of the chute of the hopper, in such position that 5 the receptacles will be below the openings at the bottom of the chute formed between the inner edge of the extensions 15 and the flanges 16.

Attached to the base of the toy is an adjustable stop member composed of a strip having a horizontal section 28 and an upwardly inclined extension 29 at each end. The stop member is pivoted upon the rivet 5 so that it may be moved in parallel adjustment with the section 1, or at right angles thereto as indicated in dotted lines in Fig. 2. When in dotted line position the finger 26, when the lever 18 is swung downwardly, will contact with the abutments 29 and be 10 caused to return without completing a full cycle of rotation. When the stop device is adjusted, as shown in full lines in Fig. 3, the lever 18 will be free to revolve throughout a complete cycle thereby permitting action 15 of the lever to be modified—in one operation making a complete circle and in the other operation having a reciprocating rotary motion.

In the operation of the toy a plurality of 30 spherical objects 30, such as marbles, are placed in the groove or runway 11, being carried successively by gravity into the chute 13 of the hopper. The lower one of the 35 series of marbles is caught and retained in the lower part of the chute 13 by the flanges 16 where it is supported. In initiating the operation of the toy a slight swing is imparted to the lever 18, whereupon the finger 26 contacts with the marble held in 40 the lower part of the chute and thereby ejected from the hopper, being guided by the extension 15 into one or the other of the receptacles 24, the flanges 25 preventing the overthrow of the marble beyond the edge of 45 the receptacle. After a single marble has been received in one or the other of the receptacles 24, the lever 18 will be carried downwardly and either complete a full cycle of rotation or be returned in its path of 50 movement, dependent upon the position of the stop member 28—29. As the lever is returned to its starting point another one of the marbles will be ejected from the hopper in the one of the receptacles 24 that is in 55 position to receive it. After initiation of the operation, the operation of the toy will continue so long as any load remains in the hopper, the marbles being ejected successively from the hopper into the receptacles 24, from which they are discharged 60 as the upper end of the lever reaches its downward position.

I am aware that the principles of the invention may find embodiment in modified structure, and I do not limit myself there-

fore to the exact construction shown and described, but what I claim and desire to secure by Letters Patent, is:—

1. A mechanical toy, comprising a frame including a support for the toy, and standards in connection with the support, a hopper removably mounted upon the standards, a revolute lever pivoted to swing in a complete cycle below the hopper and mounted in the standards, a receptacle attached to the lever adapted to receive a load from the hopper, a counterweight on the lever normally holding the receptacle in position to receive a load from the hopper, and means whereby a load is discharged from the hopper into the receptacle. 70 75 80

2. A mechanical toy, comprising a frame, a hopper mounted in the upper part of the frame, a revolute lever mounted in the frame and arranged to make a complete revolution about its fulcrum, a load-receiving receptacle at one end of said lever, a counterweight at the other end of said lever, and means for discharging a load from the hopper into said receptacle whereby said lever is caused to revolve on its pivot. 85 90

3. A mechanical toy, comprising a frame, a hopper supported in the upper part of said frame, a lever fulcrumed below said hopper and adapted to make a complete revolution about its fulcrum, receptacles attached to said lever and adapted to receive a load from the hopper, a counterweight for normally holding said receptacles in position to receive a load from said hopper, and 95 an escapement device for discharging a load from the hopper into said receptacles. 100 105

4. A mechanical toy, comprising a frame including members constituting a collapsible support for the frame and standards, a hopper removably mounted on said standards, a lever carried by a pivot pin mounted in said standards, said lever being adapted to completely rotate about its pivot pin, receptacles carried near one end of said lever, a counterweight normally holding said lever in a position for the reception of a load from the hopper into the receptacle, an escapement device for automatically ejecting a load from the hopper, and means for guiding the load from the hopper into the receptacle. 110 115

5. A mechanical toy, comprising a frame, a hopper carried by the upper part of said frame having a load-receiving member and a discharge chute, means for supporting a load in the form of spherical objects in the bottom of said discharge chute, a swinging lever pivoted below said discharge chute, receptacles carried by said lever at opposite 120 125 sides of the axis thereof, a counterweight holding said receptacles in a position to receive a load from the discharge chute of the hopper, and a finger extending into said discharge chute and carried by said lever 130

whereby the spherical objects constituting the load in the hopper are discharged successively, one at a time, from the hopper and deposited in a receptacle.

5 6. A mechanical toy, comprising a frame, a hopper mounted in said frame, a revoluble member pivoted in said frame, means for revolving said member by transferring a load from said hopper to said member, and
10 an adjustable stop device for interrupting the rotation of said member.

7. A mechanical toy, comprising a frame, a hopper mounted at the top of said frame, a revoluble member mounted in said frame,
15 a load-carrying receptacle attached to said member, and an escapement device for discharging an object from said hopper into said receptacle thereby causing said member to revolve, said escapement device being
20 operable when the revoluble member is rotated in either direction.

8. A mechanical toy, comprising a frame including upright standards and an adjustable base, a hopper mounted at the top of
25 said frame and provided with discharge openings at the bottom thereof, a rotating member mounted in said frame, a load-carrying receptacle, and a finger attached to said member at one side of the receptacle,
30 said finger being adapted to project into the bottom of the hopper to eject a load therefrom into said receptacle.

9. In a mechanical toy, the combination with a swinging member supported in an upright frame and adapted to revolve in a complete cycle, a receptacle extending at each side of one end of said member, a hopper supported above said swinging member, and an escapement for discharging an object from said hopper into either one of said
35 receptacles.

10. A mechanical toy, comprising an upright support, a hopper mounted at the top of said support, a revoluble member mounted
45 in said support and adapted to make a complete revolution, a load-carrying receptacle attached to said member, an escapement for discharging an object from said hopper into said receptacle, and a stop provided at the
50 bottom of said support adapted to interrupt the cycle of movement of said revoluble member effecting a reverse in the motion of said member after the load has been discharged from said receptacle.

55 11. A mechanical toy, comprising a frame, a hopper mounted at the top of said frame including an inclined runway adapted to receive a plurality of spherical objects, a discharge chute in communication with said
60 runway having means for supporting the

spherical objects therein, a swinging member located below the discharge chute, a receptacle carried by said swinging member extending at one side of the axis thereof, a finger projecting above the receptacle and
65 into said discharge chute, a counterweight on the opposite end of said swinging member normally holding said member in a position so that an object may be received from said discharge chute into said receptacle, and
70 means for guiding an object from said discharge chute into said receptacle after said object has been moved from said discharge chute by said finger.

12. A mechanical toy, comprising a frame, a swinging member mounted in said frame having load-receiving receptacles at opposite sides of its axis, a counterweight on the other end of said member adapted to normally hold said receptacles in upright positions, a finger in connection with said member adapted to discharge objects from a hopper into said receptacles, a hopper at the upper part of said frame including a load-receiving section and a discharge chute,
80 there being openings at each side of said discharge chute, and supports for the objects fed from said hopper into said discharge chute below said openings.

13. A mechanical toy, comprising a frame, a swinging member mounted in said frame having load-receiving receptacles at opposite sides of its axis, a counterweight on the other end of said member adapted to normally hold said receptacles in upright positions, a finger in connection with said member adapted to discharge objects from a hopper into said receptacles, a hopper at the upper part of said frame including a load-receiving section and a discharge chute, there being openings at each side of said discharge chute, supports for the objects fed from said hopper into said discharge chute below said openings, and guide walls above said
90 openings for guiding the objects from said discharge chute into said receptacles.

14. A mechanical toy, comprising a frame, a hopper mounted at the top of said frame, a revoluble member mounted in said frame and having complete rotary motion, a load carrying receptacle attached to said member, an escapement device adapted to discharge objects from said hopper into said receptacle when said receptacle approaches the hopper from either direction, and a stop device adapted to interrupt the normal rotary motion of said revoluble member, and thereby cause a rotary reciprocating motion thereof.

VINCENT S. GAINES.
